(Cl. D26—14)

FIG. 1

FIG. 2

Fig. 1 is a perspective view of a telephone set, showing our new design with the handset in place on the desk stand; and

Fig. 2 is a perspective view thereof with the handset removed from the desk stand.

The telephone set is symmetrical about its longitudinal axis and the side opposite is the same as the side shown. The dominant features of the design reside in the portions shown in full lines.

We claim:

The ornamental design for a telephone set, substantially as shown and described.
